UNITED STATES PATENT OFFICE.

JAMES GILLBREATH LESLIE, OF OREGON, ILLINOIS.

WRENCH.

SPECIFICATION forming part of Letters Patent No. 350,935, dated October 19, 1886.

Application filed March 9, 1886. Serial No. 194,558. (No model.)

To all whom it may concern:

Be it known that I, JAMES GILLBREATH LESLIE, of Oregon, in the county of Ogle and State of Illinois, have invented a new and Improved 5 Wrench, of which the following is a full, clear, and exact description.

My invention relates to wrenches, and has for its object to provide a wrench of simple, inexpensive, and durable construction, and 10 adapted to grip and turn square or round objects of various sizes, such as nuts and pipes or shafts, and adapted also for use as a vise.

The invention consists in certain novel features of construction and combinations of parts 15 of the wrench, all as hereinafter fully described and claimed.

Reference is to be had to the accompanying drawings, forming a part of this specification, in which similar letters of reference indicate 20 corresponding parts in all the figures.

Figure 1 is a side elevation, partly broken away, of my improved wrench with the movable parts in locked position, as when grasping an object. Fig. 2 is a sectional side elevation of the wrench with the moving parts 25 unlocked from the main wrench-bar, as when adjusting the movable jaw of the tool; and Fig. 3 is a cross-sectional elevation taken on the line $x-x$, Fig. 1.

30 The fixed jaw A of the wrench is fixed to the main bar B, on which the movable jaw C is fitted to slide, and to the jaw C is fixed a shank, D, which extends backward along the main bar B, and has a lug, d, also fitted to slide on the bar B.

Between the movable jaw C and the guide-lug d of shank D there is placed loosely on the main bar B a grip-plate, E, having lugs e for the passage of a strong pin, f, by which 40 the locking-lever F is pivoted to the end of the grip-plate, and to the forward end of the short arm f' of lever F there are pivoted on a pin, g, the one ends of a pair of links, G G, which extend diagonally backward and 45 across the main bar B, and at their back ends are connected pivotally with a pin, g', which crosses a recess, h, made in the back end of the shank D of the movable jaw C, said pin g' being held in slots d', made in the opposite 50 sides of shank D and ranging lengthwise of the shank. (See Fig. 1.)

In the recess h of shank D, and in front of the cross-pin g', there is placed a plate, H, between which and the base of the recess there is placed a spring, preferably an open spiral 55 spring, I, which holds the pin g' normally back against a cap-plate or cover, h', fitted over the recess h. (See Fig. 2.)

In a recess or slot, d², formed at the inner edge of the shank D there is placed a spiral 60 spring, J, within which is placed the stem k of a push-pin, K, which normally is forced forward by the spring J against the inner cross-bar, e', of the grip-plate E, and consequently tends to force the bar e' forward to 65 toward the wrench-jaw C. The edge or corner 1 of the grip-plate cross-bar e' and the edge or corner 2 of the opposite cross-bar, e², of the grip-plate bite the main wrench-bar to hold the movable jaw C to its work, as presently 70 explained. The locking-lever F has opposite side flanges, f², which overlap on opposite sides of the main bar B when the wrench is adjusted in operative position, and thereby prevent twisting of the lever or of the parts G G E 75 by the grip or force of the hand on the lever in using the tool. The wrench jaws A C have opposing plain faces a c at their one ends for gripping nuts, plates, or other flat-faced articles and at their other ends the jaws have 80 opposing toothed faces a' c', adapted to grip pipes, shafts, or other round or irregularly-shaped articles.

The operation of the wrench is as follows: When the locking-lever F is raised and swung 85 forward, as in Fig. 2, the cross-bar e' of grip-plate E will be thrown forward, and the corners 1 2 of plate E will not grip the main bar B of the tool, and the movable jaw C, shank D, links G G, grip-plate E, and lever F, with 90 attached minor parts, may be instantly moved either way along the main bar B to set the jaw C at any desired distance from the fixed jaw A of the wrench to accommodate the work. When the locking-lever F is lowered again to 95 the main bar B, as in Fig. 1, the first effect is to throw the bar e' of grip-plate E backward, while the bar e' of said plate is retained in forward position by the spring-pressed push-pin K; consequently the grip-plate E will be 100 caused backward to cause its gripping-corners 1 2 to bite the opposite edges of the main bar

B and hold the jaw C securely against back-thrust when the tool is used. As the lever F comes to rest against the back end of the main bar B, the pivot f , connecting the lever to the grip-plate E, passes beyond an imaginary straight line between the opposite end pivots, g g' , of the links G G, whereby the lever F is securely locked against the bar B, and any force exerted on or by the jaws A B and tending to push the jaw C away from the jaw A can operate only to lock the lever F more securely to the bar B, and the same force is transmitted through the links G G and the short arm f' of the lever to cause the grip-plate E to bite all the harder on the main bar B; hence the wrench will stand well to its work. While the lever F is being brought down to locking position the jaw C will ordinarily be moved gradually toward the fixed jaw A; and 20 in order to compensate for this movement and prevent breakage of the parts of the wrench should the jaw C for any reason not have a chance to move forward after the plate E has firmly gripped the main bar B, the links G G will, by their pivot g' , moving in slots d' , draw the plate H forward and compress the spring I, and said spring will receive its maximum compression about at the time the lever F settles down to full locking position against the 25 main bar B. It is obvious that the push-pin K may be dispensed with, as the outer end of the spring J may act directly on the grip-plate E. The plate H may also be dispensed with, as the pivot-pin g' may act directly on the spring I; but the pin K and plate H are preferred in practice. The forward movement of the jaw C along the main bar B as the lever F is brought down to locking position adapts the tool for use as a vise for clamping 30 and holding a variety of work. The opposite edges of the main bar B, whereon the grip-plate E bites, may be serrated, corrugated, or roughened in any approved way to facilitate prompt action of the grip-plate on the 35 bar, and the serrated bar will be preferable for wrenches intended for large heavy work.

Having thus fully described my invention, I claim as new and desire to secure by Letters Patent—

50 1. The combination, in a wrench, of a jaw, A, a main bar, B, to which jaw A is fixed, a movable jaw, C, having a shank, D, and fitted on bar B, a tilting grip-plate, E, placed loosely on and adapted to bite the bar B; a locking

lever, F, pivoted at f to plate E and extended 55 beyond the plate in a short arm, f' , and links G, pivoted at g' to the arm f' of lever F and at g to the shank D, substantially as and for the purposes herein set forth.

2. The combination, in a wrench, of a jaw, A, a main bar, B, to which jaw A is fixed, a movable jaw, C, having a shank, D, and fitted on bar B, a tilting grip-plate, E, placed loosely on and adapted to bite the bar B, a spring device, as at J K, fitted in the shank D and 60 adapted to force forward the inner bar, e' , of plate E, a locking-lever, F, pivoted at f to plate E and extended beyond the plate in a short arm, f' , and links G, pivoted at g to the arm f' of lever F and at g' to the shank D, 65 substantially as and for the purposes herein set forth.

3. The combination, in a wrench, of a jaw, A, a main bar, B, to which jaw A is fixed, a movable jaw, C, having a shank, D, and fitted 75 on bar B, a tilting grip-plate, E, placed loosely on and adapted to fit the bar B, a locking-lever, F, pivoted at f to the plate E and extended beyond the plate in a short arm, f' , links G, pivoted at g to the arm f' of lever F 80 and at g' to the shank D, said pivot g' passing through slots d' of the shank, and a yielding support, as at H I, fitted in the shank and adapted to be compressed by the pivot-pin g' as the lever F is brought to locking position, 85 substantially as herein set forth.

4. The combination, in a wrench, of a jaw, A, a main bar, B, to which jaw A is fixed, a movable jaw, C, having a shank, D, and fitted on bar B, a tilting grip-plate, E, placed loosely 90 on and adapted to bite the bar B, a spring device, as at J K, fitted in the shank D and adapted to force forward the inner bar, e' , of plate E, a locking-lever, F, pivoted at f to plate E and extended beyond the plate in a 95 short arm, f' , links G, pivoted at g to the arm f' of lever F and at g' to the shank D, said pivot g' passing through slots d' of the shank, and a yielding support, as at H I, fitted in the shank and adapted to be compressed by the 100 pin g' as the lever F is brought to locking position, substantially as and for the purposes herein set forth.
